The ornamental design for a package, as shown and described.

DESCRIPTION

FIG. 1 is perspective view of a package showing my new design having a body silhouette and the word "body";

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The dashed broken lines in the drawings depict environmental subject matter and form no part of the claimed design.
